UNITED STATES PATENT OFFICE.

DUDLEY HEPBURN STENT, OF DELHI, INDIA.

REINFORCED-CONCRETE RAILWAY AND THE LIKE SLEEPER.

Application filed January 12, 1923. Serial No. 612,238.

To all whom it may concern:

Be it known that I, DUDLEY HEPBURN STENT, subject of the King of Great Britain, residing at No. 4 Underhill Road, Delhi, 5 India, have invented new and useful Improvements in Reenforced-Concrete Railway and the like Sleepers, of which the following is a specification.

This invention relates to reenforced concrete sleepers for railways or tram ways of the separate pot or block type interconnected in pairs by a transverse bar, which serves either as a tie or a strut.

It has already been proposed to provide 15 in each pot of the sleeper a transverse tubular guide socket extending right through the pot for the reception of the respective end of the tie or strut bar.

Such transverse tubular guide socket also 20 serves the function of correctly positioning in the mould the upper and lower metallic reinforcements of the pot which are in practice tied to the guide socket, inasmuch as the two ends of the guide socket are both 25 located at and protrude from the surface of the cast concrete pot and can therefore be held in correct position relative to the respective surface of the mould.

Now for the sake of considerable economy 30 it is desirable to have the tie or strut bar as short as possible, but such short bar would be too short to extend right through both the pots of the sleeper. Hence, and also to effect economy, the tubular guide socket need not extend right through the 35 pot.

The tubular guide socket for the end of the tie or strut bar has to be properly positioned in the mould and also is correlated 40 to the correct positioning of the metallic reinforcements of the pot, and a tie or strut bar socket precariously held by one end only in the mould cannot be reliably positioned.

A member of the intertierd reinforcement 45 and guide socket can be brought to the surface of the mould and thus provide an additional positioning bearing, but in the case of the reinforcement, which is of mild steel, the exposure to atmospheric influences 50 would rapidly set up rust resulting in local if not complete disintegration of the concrete pot.

According to the present invention, a short tie or strut bar socket having a single

exposed end with means for positioning such 55 socket in the concrete are employed.

The above disadvantage of exposure of the reinforcement is overcome, by providing that the member providing additional mould bearing for the intertierd reinforcement and single exposed ended tubular guide socket is of a material resistant to atmospheric influences.

For example, a rod of the reinforcement 65 can be brought nearly to the surface and be covered by a cement or brass cap flush with the surface of the concrete.

Alternatively at a suitable point or points 70 of its length the embedded portion of the guide socket itself, which is of cast iron, may have an arm or arms extending to the surface.

A further alternative is to arrange for the 75 outer end or mouth of the guide socket, with the reinforcement secured to the latter, to protrude sufficiently from the surface of the concrete that it can be firmly positioned and held in a recess provided at the joint between the upper and lower portions of the mould, for instance either by the clamping action of the closed mould or by a transverse pin passed through the walls of the recess of the mould and the mouth of the 80 socket.

Conveniently the covering device for a 85 positioning rod of the reinforcement is arranged to serve as an abrasion or wear resistant member, being for instance a bar of cast iron on the upper surface to take the wear at the rail seat of the pot, or at the 90 portions of the under surface of the base thereof exposed to impact of beaters in packing ballast beneath the pot.

A representative example and modifications of the invention, are illustrated on the 95 accompanying drawings, in which:

Fig. 1 is a side elevation of two concrete pots interconnected by a tie bar and constituting a complete sleeper, and

Fig. 2 is a plan thereof.

Figs. 3, 4 and 5 are respectively side elevation, plan and transverse section, on a larger scale, showing the arrangement of the tie bar guide socket, the reinforcement and the abrasion bars.

Fig. 6 is a transverse section of a modification.

Figs. 7, 8 and 9 are respectively side eleva-

tion, end elevation and plan, on a still larger scale, of a rail seat abrasion resisting bar.

Fig. 10 is a fragmentary transverse sectional elevation showing an alternative method of securing the abrasion resisting bar to the reinforcement.

Fig. 11 is a fragmentary transverse sectional elevation illustrating a method of positioning the reinforcement without employing an abrasion resisting bar.

Fig. 12 is a sectional elevation of a portion of a mould with means for positioning the guide socket, and Fig. 13 is a corresponding end elevation.

a a are the two pots of the sleeper interconnected by a tie bar *b*, the ends of which bar enter tubular guide sockets *c* embedded in the pots *a*, the bar *b* being secured in each socket *c* by a single transverse cotter, pin, key or bolt *d*.

To avoid protrusion of the outer end of the socket *c* beyond the main profile of the pot *a*, so that it may not be liable to damage, the pot *a* is recessed around the outer end of the socket *c*, which latter is exposed for a length only sufficient for the reception of the single securing cotter or the like *d*. The exposed end of the socket *c* is thickened to withstand the stresses caused by the tie bar securing means.

To avoid unnecessary length of tie bar and socket, the socket *c* extends only partway through the pot *a*. Its inner end is closed to prevent inflow of wet concrete on moulding the pot *a*.

e is an upper and *f* a lower metallic reinforcement, each consisting of a grid of mild steel rods, in practice of any suitable configuration.

These two reinforcements *e* and *f* should occupy definite positions in the mass of concrete relatively to the tubular socket *c*, which latter obviously must also be positioned.

The reinforcements *e*, *f* and the socket *c* are therefore tied together, which ensures their correct mutual positions, but, owing to the socket *c* protruding at one side only, the correct position of the whole assemblage relatively to the mass of concrete, is not insured solely by the interconnection of the reinforcements and socket.

The reinforcements being of mild steel must not be exposed to atmospheric influences, therefore a more resistant exposed member is provided.

As shown in Figs. 3-5, bars *g* of cast iron are located at the surface of the concrete and connected to the upper reinforcement *e*. As the pots are usually cast inverted, these bars *g* provide the required additional bearing against the bottom of the mould, to position correctly the reinforcements *e* and *f* and socket *c* relatively to the mass of concrete forming the pot *a*.

The bar *g* may be secured as shown in Figs. 3-5 and 7-9 by hooked lugs thereon engaging around the outer hoop bar of the upper reinforcement *e*, and tied by a rod *h* bent beneath a shoulder at each end of the bar *g*; this rod *h* also ties the two reinforcements *e* and *f* together, with the inner end of the socket *c* interposed and tied to both.

Alternatively, as shown in Fig. 10, the end of the rod *h* may be passed through a hole 75 in the lug of the bar *g*.

The bars *g* serve as abrasion resisting bars beneath the rail seat. As shown in Figs. 7-9, recesses *i* may be provided in the bars *g* to receive pins passed through holes in 80 the flange of a rail, for the purpose of preventing endways movement or creep of the latter.

Similarly to the abrasion resisting bars *g* on the upper surface of the pot *a*, cast iron bars *j* may be provided at the surface of the base of the pot where exposed to the impact of beaters packing ballast beneath the pot.

These bars *j* are secured in a similar manner to the bars *g*.

Another method of providing the additional bearing in the mould, is by arms or webs, such as *k*, extending from the socket *c* to the surface of the concrete. The upper reinforcement *e* engages shoulders on the arms *k*, and additional arms *l* may extend downwards to engage the lower reinforcement *f*. As shown, lower abrasion resisting bars *j* can also be provided.

A simpler method of providing the additional bearing in the mould is shown in Fig. 11. In this construction the rod *h* which interties the upper and lower reinforcements *e* and *f* is brought nearly to the surface of the concrete and its end is covered by a cement or brass cap *m*. This cap *m* ensures the correct positioning relatively to the mould, yet, in the finished pot, protects the mild steel rod *h* from atmospheric influences.

Figs. 12 and 13 show how the guide socket *c* and the reinforcements *f* and *e* intertiered therewith, can be positioned in the mould and therefore in the mass of concrete without bringing any member, other than the mouth of the socket, to the surface of the concrete. To effect this, a recess *n* is provided in the lower portion *o* of the mould at the joint with the upper portion *p*. The protruding mouth of the socket *c* is of such length and is provided with shoulders *c'*, such that the mouth of the socket accurately seats itself in the recess *n*. Canting of the socket *c* and the reinforcements is prevented by a block *q* interposed beneath, and, if desired, secured to or integral with the upper portion *p* of the mould. This block *q* enters the recess *n* above the mouth of the socket *c* and prevents upward canting of the outer end thereof. Instead of or

in addition to the block *g*, a transverse pin *r* may be passed through holes in the side walls of the recess *n* coincident with the transverse hole through the mouth of the socket *c* for the reception of the cotter *d*.

Obviously abrasion bars *g* resting on the surface of the mould and connected to the upper reinforcement *e* and also the lower abrasion bars *j*, can be provided, even when the mouth of the socket *c* is held in a recess *n* in the mould.

The base of each pot *a* is preferably so sloped as to relieve the tie bar *b* from excessive stress.

15 *s*, Fig. 1, are the rails which are secured to the pots *a* by spikes or screws driven into wooden plug lined holes *t*.

I claim:

1. In a concrete sleeper pot, a metallic reinforcement including wear plates at the top and bottom of the pot, and a tubular tie bar guide socket exposed at one end only and correlated to and positioned by said reinforcement.

2. In a concrete sleeper pot, a metallic reinforcement, a tubular tie bar guide socket exposed at one end only, and exposed atmospheric and abrasion resistant means for positioning said reinforcement and guide socket.

3. In a concrete sleeper pot, a metallic reinforcement, a tubular tie bar guide socket exposed at one end only, and an exposed atmospheric resistant abrasion bar connected to said reinforcement.

4. In a concrete sleeper pot, a metallic reinforcement, a tubular tie bar guide socket exposed at one end only, and atmospheric resistant abrasion bars exposed at the rail seat and base of said pot connected to said reinforcement.

In testimony whereof I have signed my name to this specification in the presence of two subscribing witnesses.

DUDLEY HEPBURN STENT.
